ARMREST FOR BEDS

Sadie Bendersky, South Orange, N. J.

Application February 15, 1944, Serial No. 522,426

2 Claims. (Cl. 5—92)

1

My invention relates to beds, such as hospital beds, and it relates more particularly to beds adapted to be used for patients, invalids, or for any healthy person who wishes to spend time in bed, eating, reading, or working, while resting the lower portions of the body.

Patients or invalids who are required by their physical condition to remain in bed for a considerable length of time, and healthy individuals who spend considerable time in bed, suffer from the unnatural condition in which they find themselves. Whereas the human body is normally subjected to a continuous series of muscular actions, reactions, and reflexes resulting from the usual, normal activity of the person going about his daily business, the patient lying in bed is denied the benefits resulting from this muscular activity. In the balance of muscular actions occurring in the human body resulting from the usual motions of the healthy person, there are the actions, reactions, and reflexes of the striped muscles of the arms, legs, and body movements, on the one hand, and the unstriped muscular activity of the internal organs such as those of the digestive system on the other. When there is difficulty in performing the usual functions of the unstriped muscles, as is sometimes the case, the striped muscles are often called into play to assist the unstriped. Thus, for instance, in the ordinary experience of bowel movement, the tensing of the striped muscles of the body can often be of great assistance in elimination. Such tensing, however, requires a foundation against which the muscles can strive. This is sometimes supplied by the striped muscles of the body striving against the striped muscles of another portion of the body, as when the body is in "doubled-up position." This position is often achieved when the normal, healthy person is seated on a bowl during bowel movement.

The hospital patient or invalid is denied this, however, for the patient is required to rest in a substantially reclining position during bowel movement. Moreover, the patient does not have the benefit of the healthy stimulus to the unstriped muscles afforded by the normal action, reaction and reflexes of the striped muscles, for the patient is not permitted to use, for other than a very limited activity, the striped muscles while lying in bed. Thus, the patient or invalid is hampered in the digestion of food while, at the same time, being denied the means for assisting in the elimination of undigested food. Experiences are thus common where patients become constipated while lying in bed and require frequent medication or internal baths to

5 facilitate elimination. Such artificial means are admittedly undesirable, but physicians have been unable to find a substitute for the normal means of cooperation of the striped muscles with the unstriped muscles in effecting healthy elimination.

It is an object of my invention, therefore, to provide means on a bed to enable its occupant to utilize certain striped muscles to assist the 10 unstriped in bowel movement, while permitting the remainder of the muscles of the body to continue in a substantially resting condition.

Another object of my invention is to provide 15 a bed having means operable to afford a patient limited exercise, the extent of which is always within the control of the patient, operatively to enable the patient to render assistance to the digestive and other unstriped muscles by the exercise of the striped muscles.

20 A further object of my invention is to provide a bed having means adapted to make the condition of the occupant more comfortable.

With the above and other objects in view, my 25 invention consists of a bed comprising a head portion, a foot portion; and spaced parallel rails connecting said head and foot portions, a mattress support disposed substantially between said rails, and intermediate said head and foot portions, a mattress reclining on said mattress support; a grasp handle mounted on one of said rails and adapted to be grasped by a patient reclining on said mattress.

My invention further consists of a hospital 30 bed comprising a head portion, a foot portion, spaced parallel rails connecting said head and foot portions, a mattress support comprising longitudinal and transverse rails disposed substantially between said first-mentioned rails and intermediate said head and foot portions, and a mattress reclining on said mattress support; said

35 mattress support being adjustable and adapted to be raised or lowered, as desired, at selected portions thereof and at various angles with respect to the horizontal; means mounted on one of said rails adapted to be positioned in proximity to a portion of the body of a patient reclining on said mattress operably to enable said patient to bring said portion of said body to bear against said means during the process of elimination.

40 My invention also consists of a hospital bed including means such as heretofore defined for assisting the patient in the process of elimination, said means comprising a base upon which selected muscles of the human arm may act.

45 My invention further consists of a bed adapted

to support an occupant, said bed comprising a head portion, a foot portion, spaced parallel rails connecting said head and foot portions, a mattress-support comprising transverse rails disposed substantially between said first-mentioned rails and intermediate said head and foot portions, and a mattress reclining on said mattress-support; said mattress support being adjustable and adapted to be raised or lowered, as desired, at a selected portion thereof and at an angle to the horizontal; an arm rest; and means associated with said mattress support for removably securing said arm rest to said bed, operably disposing said arm rest in position to support an arm of said occupant.

For the purpose of illustrating my invention, I have shown in the accompanying drawings forms thereof which are at present preferred by me, since the same have been found in practice to give satisfactory and reliable results, although it is to be understood that the various instrumentalities of which my invention consists can be variously arranged and organized and that my invention is not limited to the precise arrangements and organizations of the instrumentalities as herein shown and described.

With reference now to the drawings in which like reference characters indicate like parts:

Figure 1 represents a perspective view of a hospital bed embodying my invention, and a patient resting thereon in the act of elimination in accordance with my invention.

Figure 2 represents a fragmentary perspective view of a grasp handle and arm rest unit, mounted on the rail of a bed, embodying my invention.

Figure 3 represents a sectional view of a grasp handle and arm rest unit mounted on a hospital bed, with the arm rest disposed in an "out-of-the-way" position, embodying my invention.

Figure 4 represents a perspective view of a modified embodiment of my invention comprising a grasp handle and arm rest unit mounted on a bed.

Figure 5 represents a vertical sectional view of the modified embodiment of my invention illustrated in Figure 4 and showing the arm rest in an "out-of-the-way" position.

Figure 6 represents a fragmentary view of the rear of a chassis and rail assembly embodying my invention, illustrating a means for locking said chassis to the rail.

Figure 7 represents a perspective view of another embodiment of my invention.

Figure 8 represents a perspective view of an arm-rest assembly of modified construction embodying my invention.

Figure 9 represents a perspective view of a further modified construction embodying my invention.

Figure 10 represents a perspective view of the head and upper portion of a bed of another modified construction embodying my invention.

Figure 11 represents a side view, partly in section, and greatly enlarged, of the modified construction illustrated in Figure 10, embodying my invention.

Figure 12 illustrates a fragmentary, sectional view of a modified construction of the embodiment of my invention illustrated in Figure 10, and embodying my invention.

Figure 13 illustrates a fragmentary view of a further modified construction of the embodiment of my invention illustrated in Figure 10, and embodying my invention.

Figure 14 represents a perspective view of another modified construction of the embodiment of my invention illustrated in Figure 10, and embodying my invention.

It is to be understood that wherever the phrase "hospital bed" is used, it is to be considered as applying as well to any bed, whether used or adapted to be used in a hospital or not, the term "hospital" being illustrative only. However, the conditions prevailing in hospitals are aptly suited for illustrating the needs of a patient or invalid in a bed such as that embodied in my invention. Thus, whereas means for exercising a patient or for aiding in elimination are highly desirable, yet it is also of prime importance that no impedimenta be presented between the patient and the nurse, interne, or physician who must frequently have free access to the body of the patient. It is, therefore, important that whatever aids are afforded the patient be either of small size, of facile mobility in removal when desired, or both.

Moreover, a convalescing patient who, although needing little care, spends virtually all of his time in bed, is subjected to bed sores, constipation and other unpleasant results if comforting and relaxing means are not provided for permitting limited but constructive exercise of selected muscles, while resting other selected portions of the body.

Nevertheless, it is to be understood that my invention is equally adapted for use by healthy persons who desire to "sit up" in bed, resting, reading, or eating there in a relaxed position.

In accordance with my invention, I provide a bed 10 which may be of a standard hospital bed design, or may be of any desired structure. This bed comprises a head portion 11, a foot portion 12, spaced parallel rails 13 and 14 connecting said head and foot portions, and a mattress support 15 mounted on said rails. If desired, the mattress support 15 may be adjustable, such as that illustrated in Figure 1, so as to enable a patient to rest in a seated position, a semi-reclining position, or in a reclining position, at the will of the physician or otherwise as desired. A suitable mattress 16 is disposed on said mattress support 15. Each rail 13 and 14 comprises an angle iron having a vertical-walled bar portion 23 and an upper, horizontal-walled bar portion 24 integrally formed therewith.

A mounting unit, or chassis, 17 is disposed on the rail 13, and a similarly constructed mounting unit, or chassis, 18 is disposed on the rail 14. For purposes of description, I shall describe in detail the chassis 17 with respect to the rail 13; and it is to be understood that the chassis 18 may be similarly constructed with respect to the rail 14.

The chassis 17 consists of a panel 19 juxtaposed to the outside face 20 of the rail 13. A slide bearing 21 is vertically disposed along one edge of the panel 19, and a roller bearing assembly 22 projects toward the median axis of the bed, and embraces, and is adapted to roll upon, the horizontal, bar portion 24 of the rail 13.

The roller bearing assembly 22 may be constructed in the following manner: Horizontally disposed rollers 25 and 26, preferably having an outer bearing surface of rubber or other suitable material, are respectively rotatably mounted on spindles 27 and 28, disposed along a horizontal plane intercepting said vertical panel 19. The spindles 27 and 28 are mounted on said panel in a cantilever manner and project from the inner face of said panel toward the median axis of said bed. A roller-mounting panel 29 is secured to

the inner ends of the spindles 27 and 28, and is carried hereby, said roller mounting panel 29 being spaced from the panel 19 sufficiently to embrace the horizontal-walled bar portion 24 of the bed-rail 13 therebetween. Suitable rollers 30 and 31 formed of rubber or other so-called "silent roller" material are respectively mounted on suitable spindles 32 and 33 disposed along a horizontal plane beneath the plane of the spindles 27 and 28; said spindles 32 and 33 being mounted on the outer face of the roller mounting panel 29, and projecting outwardly toward the panel 19. The lower edge of the panel 19 is inwardly turned as at 34 a distance below the lower edge of the rollers 25 and 26 equal to the height of the vertical-walled bar 23 plus sufficient space to allow free longitudinal motion therealong.

In operation, the rollers 25 and 26 rest upon the horizontal bar 24, and are retained in longitudinal and parallel moving relation to the rail 13 by the panels 19 and 29 depending from said rollers 25 and 26 and embracing said rail. The rollers 30 and 31 outwardly projecting from the roller-mounting panel 29 along a horizontal plane disposed beneath that of the spindles 27 and 28, enable said rollers 30 and 31 to be carried by said roller-mounting panel 29 beneath the horizontal-walled bar 24, and yet to prevent vertical angular displacement of said roller bearing assembly during longitudinal movement thereof, as well as to prevent angular displacement of the whole mounting unit 17 during the use thereof by the patient, which use will be more fully described hereinafter.

The inwardly turned edge 34 of the panel 19 serves to cooperate with the rollers 30, 31 to prevent upward displacement of the mounting unit when in use.

The slide bearing 21 comprises a vertical stanchion 35 secured to the panel 19 by any suitable means such as the weld 36. A hollow, slide bearing 37 is formed through the upper face 38 of the stanchion 35 and projects downwardly through said stanchion 35 to a step-bearing 39 comprising the lower end of said slide bearing 37. A key-way 40 extends vertically along said slide bearing 37 through a substantial portion thereof.

A vertical shaft 41 of an external diameter slightly less or substantially equal to the internal diameter of the slide bearing 37 is adapted to be inserted into said slide bearing, and is limited against rotation therein by means of a key 42 projecting outwardly from one side of said shaft 41. The lower end 43 of the shaft 41 is adapted to rest upon the step bearing 39. The upper end 44 of the shaft 41 is secured by any suitable means, such as "freezing," welding, or integral formation with a horizontal arm 45 adapted to project inwardly toward the median axis of the bed when the shaft 41 is inserted within the slide bearing 37. An arm rest 46 is secured to the arm 45, or otherwise projects therefrom, and is formed according to any suitable contour or conformation. If desired, this arm rest may comprise a portion 47 adapted to sustain the forearm, a hand receiving portion 48, and an elbow nest 49. Also, if desired, the arm rest 46 may be suitably padded.

A lug 50 is mounted on the outer face of the panel 19 and has vertically disposed therethrough a slide bearing 51 opening through both the upper and lower faces of said lug 50, said slide bearing 51 being of a diameter substantially equal to the slide bearing 37. A key-way 52 is disposed along

said slide bearing 51 along the side thereof opposite to the side of the slide bearing 37 along which the key-way 40 is formed.

A grasp handle 53 is mounted on the upper edge of the panel 19, and said panel 19 is hollowed out as at 54 to enable the fingers of a hand to pass therethrough in order to grasp said handle 53.

A suitable latch 55 is mounted on the inner face of the panel 19 and is adapted to interlock with any of a series of interstices 56 disposed within the horizontal bar portion 24 of the rail 13, at the will of the patient, nurse, or other attendant. The interstices 56 may consist of holes drilled or otherwise formed through the bar 24, undulating crevices (not shown) formed on the upper face of said bar, or they may be formed in an auxiliary bar (not shown) mounted on the rail 13 and adapted to sustain the rollers 25 and 26 as well as interlock with the latch 55.

If desired, the slide bearing 37 may be formed without a key-way, as illustrated in Figure 1. In the assembly therein illustrated, the upper face 38 of the stanchion 35 serves as a step bearing for the key 42 projecting from the shaft 41, and a suitable stud-bolt 57 is disposed through the stanchion 35 of said assembly and is adapted to hold the shaft 41 against rotation therein.

In operation, the chassis 17 is rolled out along the rail 13 until it is in suitable position with respect to the body of the patient 60, whereupon the latch 55 is inserted in the nearest interstice 56, to hold the unit against longitudinal displacement along the rail 13. The shaft 41 is then inserted through the slide bearing 37, thereby bringing the arm rest 46 into operable position with respect to the body of the patient 60. The patient can then rest her arm on the rest 46, as desired for her comfort. During bowel movement, moreover, she is now in proper position for exerting muscular pressure against the elbow nest 49 and the hand rest 48, thereby tensing striped muscles in her body to assist the unstriped muscles in evacuating the bowels. By this means, only a selected group of muscles is tensed, while all the remainder of the muscles of her body are permitted to remain at rest.

When it is desired to remove the arm rest from its position in proximity to the patient's body, it is merely necessary to lift it out of the slide bearing 37, turn it upside down, and pass its shaft 41 vertically upward through the slide bearing 51 of the lug 50. In doing this, it is necessary to rotate it one-half turn in order to permit its key 42 to pass through the key-way 52 of the lug 50. When this is done, the arm rest is then again rotated one-half turn operably to cause the lug to slide along the upper face 59 of the lug 50 as a step bearing and to dispose the arm 45 and arm rest 46 beneath the bed in an "out-of-the-way" position, as illustrated in Figure 3.

When the patient is in fully reclined position on the bed 10, she is enabled to grasp the handle 53 to assist her in turning or moving about in the bed, and also to enable her to hold on to something solid for purposes of mildly exercising the striped muscles of her arms, chest, abdomen, etc., said exercise being adapted to invigorate the unstriped muscles of her body so as to strengthen them for normal action. Moreover, the grasp handle 53 is likewise adapted to be used by the patient for exerting muscular tension to assist her in bowel movement.

When it is desired to withdraw the mounting

unit from its operative position with respect to the patient, it is merely necessary to suspend the arm rest 46 through the lug 50 as hereinbefore described, release the latch 55 and roll the mounting unit rearwardly toward the head of the bed. It is then in a completely "out-of-the-way" position, and is available for return to operative position whenever desired; such return being effectuated by merely rolling the mounting unit forward to its desired location and latching it to the rail 13, thereby anchoring it in place.

In Figures 4, 5, and 6 is illustrated a modified embodiment of my invention. In this embodiment, I provide a mounting unit, or chassis, 62 comprising a vertically disposed panel 63, a roller assembly 64, similar to the roller assembly 22, a stanchion 65, and a grasp handle 66 mounted on the panel 63 and forwardly projecting therefrom. A latch 67 is disposed on the inner face of the panel 63. This latch is pivoted to said panel, as at 68 and is shaped in the form of a bell-crank. One arm of the bell-crank latch projects downwardly as at 69 and is adapted to interlock with an interstice 70 in the rail 13. The other arm of the bell-crank latch 67 extends upwardly and is shaped at its outer end into a finger-receiving portion 71. A leaf-spring 72 is secured at one end 73 thereof to the inner face of the panel 63, and bears towards its other end against the forward face 74 of the upper arm 75 of the bell-crank 67 operably to urge the lower arm 69 of the bell crank into the interstice 70, thereby latching the chassis 62 against longitudinal displacement with respect to the rail 13.

The stanchion 65 has formed therein a bearing 76 opening through the upper end 77 of said stanchion. This upper end 77 is a step bearing adapted to support a block 78. A shaft 79 projects downwardly from the block 78 and into the bearing 76; and is either "frozen" against rotation therein, or is otherwise locked in any desired manner against such rotation. A block 80 of conformation similar to the block 78 is mounted on one leaf 81 of a hinge 82, and secured thereto by any suitable means such as screws (not shown). Another leaf 83 of said hinge 82 is secured to and mounted on, the upper face of the block 78. A post 84, preferably formed integrally with the block 80 projects upwardly therefrom, and is pivotally secured at its upper end to one end of a horizontally disposed arm 85 by means of a vertically disposed trunnion 87. The other end of the arm 85 is secured to an arm rest 86.

In operation, the arm 85 and arm rest 86 are swung about the trunnion 87 as a pivot, until the arm rest 86 is in proper location with respect to the body of the patient to enable said patient to recline on said arm rest 86. When it is desired to dispose of the arm rest 86, it is merely necessary to lift the arm rest 86 and rotate it about the hinge 82 until the block 80, post 84, and arm 85 are freely suspended therefrom; the arm 85 is then rotated about the pivot 87 until the arm rest 86 is located beneath the bed.

When it is desired to again use the arm rest 86, it is merely necessary to swing the arm 85 outwardly about the trunnion 87, and to lift the post 84 about the hinge 82 until the leaf 81 supporting the block 80 rests upon the leaf 83 mounted on the block 78. If desired, any suitable means such as the stud-bolt 88 may be utilized adjustably to fixate the arm 85 on the trun-

nion 87 when it is being positioned with respect to the patient 80.

In Figure 7 is illustrated another modified embodiment of my invention. In this embodiment the chassis 90 comprises a body structure 91, made of sheet material such as sheet metal, mounted on the rail 13 by means of a roller bearing assembly 92 similar to the roller bearing assembly 22. The sheet material body 91 comprises a base portion 93 and a grasp handle portion 94 forwardly projecting therefrom. The base portion 93 has formed therein a double-slotted recess 95 extending vertically through its top portion 96. This double-slotted recess 95 is formed by folding the sheet material inwardly and rearwardly against itself, as at 97, and then bending it inwardly and forwardly as at 98 to form a forwardly projecting wall 115 in spaced relation to the rearwardly folded material 97 and parallel to the plane of the original sheet material 93. The forwardly projecting wall 115 is then outwardly and rearwardly bent at 101 until it is projecting rearwardly as at 99, when it is once more folded, this time outwardly and forwardly upon itself as at 100 until the metal again projects forwardly in the same plane as the original metal 93. The folds 97 and 100 are preferably spaced a distance substantially equal to one-third the distance between the bends 98 and 101. If desired, a base lug 102 may be outwardly struck out of the bottom portion of the forwardly projecting wall 115 intermediate the folds 97 and 100, said lug 102 projecting into the downward path of the recess 95. If desired, a similar recess 103 may be formed on the chassis 90 intermediate the recess 95 and the grasp handle 94. The roller bearing assembly 92 is secured to the body portion 93 through suitable radial bearings 104.

A suitable latch 105 is secured preferably to the rearward portion of the chassis 90 and is adapted to interlock with suitable interstices 58 on the bed rail 13.

A vertical shaft 106 is formed of sheet material such as sheet metal and is crimped so as to form the slide panels 107 and 108 disposed along one plane and an intermediate rib 109 outwardly projecting therefrom; the rearward and forward edges of the slide panels 108 and 107 being spaced substantially equal to, or slightly less than the space intermediate the rearward bend 98 and forward bend 101 of the double-slotted recess 95, the width of the rib 109 being substantially equal to or slightly less than the space intermediate the rearward fold 97 and forward fold 100 of said recess 95, and the thickness of the slide panels 107 and 108 being substantially equal to or slightly less than the space between the forwardly projecting wall 115 and the reverse folds 97 and 100. The vertical shaft 106 is thus adapted to be slid into the recess 95, and to project downwardly there-through until the lower edge 110 thereof abuts or rests upon the lug 102.

The upper portion of the shaft 106 is inwardly bent as at 111 to form a horizontal portion 112. This horizontal portion 112 is downwardly bent along both its forward and rearward sides as at 113 and 114, and then bent generally toward the median axis of the horizontal portion 112, operably to form a sleeve having a solid upper wall 116, side walls 113 and 114 and a split bottom wall 117. The outward edges 118 of the split bottom wall bear against the inner faces of the vertical slide panels 107 and 108 operably to render additional support for the horizontal por-

tion 112. A slide shaft 119, which may be made of sheet material is adapted to be disposed within the sleeve 112. This shaft is of a thickness and width substantially equal to the internal thickness and width of the sleeve 112 and is adapted to be frictionally or otherwise held against undesired longitudinal displacement therealong, said friction or other holding means being insufficient however to retain said shaft against such displacement when it is desired intentionally to extend said shaft 119 outwardly from, or inwardly to, said sleeve 112. An arm rest 120 is mounted on the inward portion of said shaft 119 and is of such contour, texture, and position as to render it adaptable for supporting the arms of a patient sitting up in the bed.

In operation, when it is desired to withdraw the arm rest from juxtaposition to the patient, it is merely necessary to lift it with its vertical shaft 106 out of the double slotted recess 95, turn it upside down, with the arm rest 120 positioned beneath the bed, and reinsert the shaft 106 upwardly through the bottom portion of the double slotted recess 103. A suitable retaining means such as a locking pin 121 having a thumb release 122 may be used to retain said shaft against undesired downward displacement through the recess 103. When the locking pin 121 is used, a suitable recess such as the interstice 123 may be formed through the vertical shaft 106, and adapted to receive the locking pin 121 in interlocking relation therewith. The outwardly extending rib 109 of the vertical shaft 106 prevents this shaft from being inserted through the recess 103 in reverse position, with the arm rest portion extending outwardly instead of beneath the bed. If desired, the grasp handle 94 may be formed into a circular or semi-circular shape as shown, operable to render it more comfortable for grasping.

In Figure 8 is shown a modified embodiment of my invention wherein the arm rest 120 is mounted on the vertical shaft 106 by means of a horizontally disposed slide shaft 112 extending into a sleeve 113 mounted on the vertical shaft 106. Adjustment means 124 are provided for fixatingly adjusting the distance between the arm rest 120 and the shaft 106. In this embodiment of my invention, the friction between the horizontal shaft 112 and the sleeve 113 may be reduced to a minimum, and any one of various retaining means such for instance as the thumb screw 125 may be used to hold said shaft 112 against displacement within the sleeve 113.

In Figure 9 is illustrated another modified embodiment of my invention, wherein the vertical shaft 106 is disposed through double slotted recesses 126 formed between the bed rail 13 and the retaining bar 127. The retaining bar 127 is preferably formed of a sheet material such as sheet metal and is securely mounted on the bed rail by means of suitable retaining means such as the screws 128. Intermediate the screws 128, the retaining bar is formed into a series of recesses 126, preferably each of which is formed in the following manner: The bar is outwardly bent as at 129 until it has traversed a distance from the rail 13 equal to or slightly greater than the thickness of the slide panels 107 and 108, whereupon the bar is bent forwardly to form a vertical wall 130 substantially parallel to the vertical wall portion 23 of the bed rail 13. The vertical wall 130 is then extended forwardly a distance substantially equal to the width of the slide panel 108, whereupon it is bent outwardly, forwardly and then inwardly to form a recessed wall 131 of a conformation and

internal measurement substantially similar to the conformation and external measurement of the rib 109 of the vertical shaft 106. The retaining bar is then bent forwardly to form a retaining wall 132 along the same plane as the retaining wall 130 until it has traversed substantially the width of the vertical shaft 106, whereupon it is inwardly bent and reversely folded upon itself as at 133. The inner edge of the reverse fold 133 extends inwardly sufficient to traverse the thickness of the slide panel 107 and to bear against the vertical wall 23 of the bed rail 13. The reverse fold 133 then begins the next adjacent recess 126.

In operation, the vertical shaft 106 may selectively be disposed through any of the recesses 126 according to the requirements of the position of the patient in the bed. Suitable recesses 134 may be formed in the vertical shaft 106, adapted to interlock with any desired retaining means, such as the pin 135 flexibly secured to the shaft 106, when said retaining means or pin 135 has been passed through the co-aligning recess 136 on the retaining bar 127, operably to retain said shaft 106 against vertical displacement within any of the recesses 126. When it is desired to withdraw the arm rest 120, from the upper portion of the bed, it is merely necessary to withdraw the retaining pin 135 from the retaining bar 127 and to lift the shaft 106 out of the recess 126. The shaft 30 may then be turned upside down and re-inserted through one of the recesses 126, and the retaining pin 135 re-inserted through the recess 136 and co-aligned recess 134, to interlock the shaft against vertical displacement within the recess 126.

In Figures 10 and 11 are illustrated a further embodiment of my invention, wherein arm rests are brought into proximity to the body of the patient, and are readily removable therefrom at

40 will.

According to this embodiment of my invention, I provide a frame 140 adapted to be mounted on the mattress support, such as the frame 15 of the bed spring, and preferably at the head portion 141 thereof. This mattress support comprises generally an angle iron having a bar portion 142 disposed substantially along the plane of the lower side 143 of the mattress 16, and a bar portion 144 disposed generally perpendicular to the bar portion 142 and extending downwardly when the head portion 141 is lowered to the horizontal position.

The frame 140 comprises generally, spaced, parallel longitudinal arms 145 and 146 adapted to rest upon the mattress 16, and extend from the "head" portion thereof to proximity to the "waist" portion thereof; and spaced, parallel cross arms 147 and 148 perpendicularly connecting said arms 145 and 146 substantially at the "head" and "waist" portions thereof respectively. The arms 147 and 148 may be connected to the arms 145 and 146 by welding, soldering, riveting, or otherwise, and may be coplanar therewith, or one mounted above the other, as desired. The upper ends of the arms 145 and 146 are bent downwardly as at 149 and 150, preferably at right angles to the arms 145 and 146, to proximity to the bar 144, whereupon it is bent forwardly and reversely bent upon itself as at 150 so as to form a hooked end 151 adapted to bear against the inner face 152 of the bar 144. A suitable locking member such as the eccentrically pivoted lever 153 is mounted on each of the downwardly projecting arms 149 and 150 and is adapted to bear against the outer face 154 75 of the bar 144 and to force the arm 149 away

11

from its hooked end 151 against the spring tension thereof when the handle 155 of the lever 153 is turned downwardly to a locking position. When the handle 155 is pulled upwardly about the eccentric pivot 156 thereof, the hooked end 151 is released from the bar 144, thereby unlocking the same.

Spaced, parallel arm rests 157 and 158 are respectively mounted on the cross arm 148 in general proximity to the longitudinal arms 145 and 146, and are adapted to be disposed one on either side of a patient resting in the bed. Although it is possible to dispose the arm rests 157 and 158 upon the longitudinal arms 145 and 146, a preferable embodiment of my invention comprises the arm rests 157 and 158 disposed intermediate the longitudinal arms 145 and 146. By this disposition of the arm rests, it is assured that when the patient rests on one of the arms as for instance the arm 157, the point of application of force is disposed intermediate the fulcrum 149 and the center of gravity 162 of the frame 140. By this means, the stability of the frame is assured, and the increase of pressure of the patient's body upon the arm rest only increases the pressure of the frame bearing upon the frame mounting structure, operably to increase the locking action thereof. Suitable covering material, such as the wrappings 159 which may include padding (not shown) is disposed about the longitudinal arms, cross arms, and arm rests, as desired.

In operation, when it is desired to use the frame, the head portion 141 of the mattress support is raised by the means provided in the hospital bed until it is inclined at the desired angle. The frame 140 is then slipped over the head portion of the mattress 16, with the downwardly projecting arms 149 and 150 of the frame extending over the upper edge 160 of the mattress, and the cross-arm 148 resting upon the upper face 161 of said mattress 16. The upper portions 163 of the longitudinal arms 145 and 146, are then pressed downwardly and rearwardly against the mattress so as to project the hooked ends 151 beyond the under edge of the bar 144. The frame 140 is then pulled downwardly and forwardly until the hooked ends 151 pass forwardly of the lower edge of the bar 144, whereupon the frame is released by the one assembling. The spring action of the mattress thereupon automatically urges the longitudinal arms 145 and 146 upwardly and forwardly, carrying with them the respective downwardly projecting arms 149 and 150, each of which carries with it the hooked end 151. In doing so, the hooked end 151 embraces the bar 144 in interlocking engagement therewith. The handle 155 of the eccentrically pivoted locking bar 153 is then turned downwardly against the spring tension of the hooked end 151, operably to lock the downwardly projecting arms 149 and 150 against displacement with respect to the bar 144 of the bed spring frame 15. The arm-rests 157 and 158 are now firmly secured in place.

If desired, a pillow 164 may be mounted on the frame 140 in the following manner: The pillow is set up lengthwise between the arm rests 157 and 158, with one end 165 projecting above the cross-arm 147. The upper extremity 166 of this end portion 165 is then tucked securely between the cross-arm 147 and the mattress 16, thereby holding the pillow 164 in place operably to serve as a body back rest for the patient; and a padding protecting the patient's body from contact with both cross-arms 147 and 148. If further

12

padding is desired, a second pillow 167 may be disposed over the first pillow 164, in a cross-wise manner, the second pillow 167 resting upon the rearward portions of the arm rests 157 and 158. When this is done, the pillow 167 protects the patient's body from contact with the longitudinal arms 145 and 146, and gives a complete padded back-rest support in all directions.

In Figure 12 is illustrated a modified embodiment of my invention whereby the frame 140 is secured to the bar portion 144 without the necessity of using a locking lever. By this embodiment, I provide a mounting unit or retaining bar 168 having a downwardly projecting hook 169 extending upwardly and rearwardly from the upper portion thereof. This mounting unit 168 is permanently secured to the rearward face 154 of the bar portion 144 by any suitable means such as the rivet 170, nut-and-bolt assembly, or other suitable means. The frame 171 of this embodiment of my invention is substantially identical with the frame 140 with the exception that instead of the downwardly projecting arms 149 and 150, this frame 171 is provided with similar downwardly projecting arms 172, each of which project downwardly an extent sufficient to traverse the hook 169 on the mounting unit 168. The orifice 173 extends through each of the downwardly projecting arms 172 and is adapted to enable the hook 169 to pass therethrough. In operation, when it is desired to use the frame 171, it is merely necessary to place the frame upon the mattress in the general position which it will have when it is ready for use, with the downwardly projecting arms 172 in operative juxtaposition to the mounting units 168. The upper portions 163 of the longitudinal arms of the frame 171 are then pressed downwardly and rearwardly against the spring action of the mattress 16, until the orifices 173 are presented to the hooks 169, whereupon the frame is pulled downwardly and forwardly until the hooks 169 have passed through the orifices 173, whereupon the frame is released permitting the spring action of the mattress to force it upwardly, thereby interlocking the downwardly projecting arms 172 with the hooks 169.

In Figure 13 is illustrated another embodiment of my invention whereby other means are provided for securing the frame to the bar 144 without the use of a lever. In this embodiment, the frame 174 is provided having downwardly projecting arms 175 and 176, the lower ends of which are turned in a forward direction as at 177 and 178. These ends 177 and 178 are preferably perpendicular to the downwardly projecting arms 175 and 176. The bar 144 has formed therethrough interstices 179 and 180 adapted to receive and interlock with the respective ends 177 and 178 of the downwardly projecting arms 175 and 176.

In operation, when it is desired to use the frame 174, it is placed upon the mattress 16 in a position substantially similar to that which it will maintain in its secured condition, with the downwardly projecting arms 175 and 176 extending over the upper edge 160 of the mattress 16, with the ends 177 and 178 in juxtaposition to the entrance of the interstices 179 and 180. The cross-arm 147 is then grasped at its center and is pulled downwardly and forwardly operably to draw with it the ends 177 and 178, projecting them into interlocking engagement with the interstices 179 and 180. The frame 174 is then securely in place.

In Figure 14 is illustrated a further embodiment of my invention, whereby means are provided for lodging the frame firmly on the mattress, without resorting to anchoring the frame on the bar 144. In this embodiment of my invention, I provide a frame 181 of conformation and structure substantially similar to that of the frame 174, with the exception of the downwardly projecting arms. In the frame 181, I provide instead, arms 182 and 183, which project downwardly only to proximity to the median height of the mattress 16. A cross-bar or anchoring bar 184 extends between, and is secured to, the forward faces of the downwardly projecting arms 182 and 183 by any suitable means such as the rivet 185.

In operation, when it is desired to use the frame 181, it is merely laid on the upper surface 161 of the mattress 16 and is drawn forwardly until the anchoring bar 184 bears against the upper edge 160 of the mattress 16. When the patient rests his weight on the arm rests 157 and 158, or either of them, the force of said weight is transmitted through the frame to the anchoring bar 184 which bears against the upper edge 160 of the mattress 16 operably to transmit said force thereto. In the usual structure of mattresses of the type used in hospital beds, the upper edges 160 are of firm build and adapted to resist lateral forces, such as would be transmitted thereto in this case. As illustrated in Figure 14, the outer edges 186 of the anchoring bar comprise a leading edge formed at right angles to the forward surface of the bar, said leading edge being adapted to bear against the mattress material whenever there is any tendency toward lateral motion of the frame, operably to resist said motion and to anchor the frame in place.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

What I claim as new and desire to secure by Letters Patent is:

1. An arm rest assembly adapted to be used in conjunction with a bed comprising a body supporting portion and a rail; said arm-rest assembly comprising a mounting section, means securing said mounting section to said rail, a post, an extension arm swingably secured to one end of said post for movement about a vertical axis, means

for securing said extension arm fixedly in adjusted position on said post, an arm rest carried by said extension arm, and horizontal pivot means securing the other end of the post to said mounting section, for pivotal movement of the post about an axis parallel to said rail, the construction and arrangement being such that the arm rest may be located in operative position over said body supporting portion or swung to inoperative position under said body supporting portion.

2. An arm rest assembly adapted to be used in conjunction with a bed comprising a body-supporting portion and a rail disposed generally along one side of said body-supporting portion; said arm rest assembly comprising a mounting section, means securing said mounting section to said rail, a post supported by said mounting section and having a substantially vertical axis; and a substantially horizontally disposed arm rest rotatably supported by said post and movable about said axis and over said body supporting portion, and said post comprising members hinged together along an axis transverse to said first named axis and substantially parallel to said rail, said arm rest being positioned beneath said body supporting portion when one of said members is rocked downward about said hinge axis and said arm rest is turned about said vertical axis.

SADIE BENDERSKY.
